UNITED STATES PATENT OFFICE

CHARLES H. COULSON, OF HANOVER, PENNSYLVANIA

SHOE HEEL

Application filed August 30, 1929. Serial No. 389,540.

My invention relates to shoes and more particularly to heels.

It is an important object of my invention to provide a leather heel so constructed that all the benefits of the usual rubber heel are obtained.

It is a further object to construct a heel that is light in weight, comfortable and more durable than the usual type of heel.

10 It is a further object to construct a heel of a plurality of superposed leather lifts having cushioning means for absorbing the shocks caused by walking.

It is a further object to construct a heel of 15 a plurality of superposed leather lifts having felt inserts causing a much tighter seat between the heel and the sole of the shoe.

Further objects will appear from the detail description taken in connection with the 20 accompanying drawings, in which:

Figure 1 is a partial view of a shoe having my new and improved heel attached thereto,

Figure 2 is a top plan view of my heel detached from the shoe,

25 Figure 3 is a sectional view taken on line 3-3 of Figure 2,

Figure 4 is a sectional view of a modified form of the invention,

Figure 5 is a sectional view of another 30 modified form of the invention, and

Figure 6 is a perspective view of one of the heel lifts having the felt insert.

In the drawings, 1 represents a shoe to which my new and improved heel 2 is attached in any well known manner.

The heel 2 is constructed of a plurality of superposed leather lifts 3 and 4 each having an opening in the center to receive a felt pad 5. The leather lifts 3 are cupped out 40 as shown at 6 in Fig. 6 of the drawing and are alternately spaced from the lifts 4 at the upper portion of the heel.

The heel is thus constructed of a plurality of leather lifts one placed upon the other, 45 the lifts 4 fitting in the cupped lifts 3 allowing a certain amount of resilience and the felt pads 5 placed one upon the other acting as a cushion and absorbing the shocks caused by walking.

50 After the lifts are placed together they are

cemented or glued to form a tight fitting, compact heel. To finish off the heel a pair of solid leather lifts 6^a of the general contour of the lifts 3 and 4 are nailed or otherwise attached to the lifts 4.

55

In the modified form of my invention shown in Fig. 4 of the drawing, the heel is constructed of alternate perforated lifts 7 and the lifts 3^a carrying the felt pads 5. The lifts are held together as hereinbefore described. By this construction, the combination of the felt pads 5 and the openings 8 of the perforated lifts 7 act to cushion the heel against shocks necessitated by walking.

60

In the form shown in Fig. 5 of the drawing, the heel 2 is constructed of an upper lift 3^b having the felt pad in the center thereof and a plurality of lifts 8 having openings 9 in the center. These openings form an air space in the center of the heel giving a light 70 weight heel and adapting it to act as a cushion.

65

It will thus be seen that I have constructed a leather heel that is strongly built light in weight and one that will give comfort to the 75 wearer. By the use of the felt pads the heel will adhere better to the sole of the shoe, since felt is more adhesive than hard leather, after glue or cement is applied.

It will further be seen that I have combined these features of shock absorption, comfort, tight fitting seat, and all the superior wearing qualities of a solid leather heel combined with the center filling of felt 80 or other named light weight materials producing a heel with all the qualities of either solid leather or rubber plus distinctively lighter weight, superior to all other types of heels.

85

90 What I claim is:

1. A heel comprising a plurality of superposed lifts, certain of said lifts having a cupped-out upper surface, others of said lifts fitting within the cupped-out lifts, each of the several lifts having an opening there-through, a plurality of felt pads fitting said openings and in superposed relation, and solid leather outer lifts covering and secured to the aforesaid lifts.

95

2. A heel comprising a plurality of super-

100

- posed lifts, certain of said lifts having cupped-out upper surfaces, and having an opening therethrough, other lifts superposed on the cupped-out lifts, said second-named lifts having an opening therethrough, the openings in the lifts registering, a felt pad fitted within the openings of the pairs of lifts, and solid leather outer lifts covering and secured to the aforesaid lifts.
- 10 3. A heel comprising a plurality of superposed lifts having aligned openings therethrough, felt pads received within the openings in said lifts, certain of said lifts being formed with a depression in one face thereof
15 adapted to form a cushioning chamber with a next adjacent lift, and an imperforate outer lift covering and secured to the aforesaid lifts.

CHARLES H. COULSON.
